UNITED STATES PATENT OFFICE.

MORRIS ROSENWASSER, OF NEW YORK, N. Y.

APPARATUS FOR USE IN MANUFACTURING LEGGINGS.

1,137,087.

Specification of Letters Patent. Patented Apr. 27, 1915.

Application filed February 7, 1912. Serial No. 676,088.

To all whom it may concern:

Be it known that I, MORRIS ROSENWASSER, residing in the city, county, and State of New York, have invented certain new and useful Improvements in Apparatus for Use in Manufacturing Leggings, of which the following is a specification.

This invention relates to certain new and useful forming or shaping apparatus, which is particularly useful in connection with the manufacture of leggings or similar articles.

One of the objects of the invention is to provide an apparatus of the kind referred to which is adapted to give shape to a tubular blank.

Another object is to provide a new and improved apparatus of the kind referred to which is adapted to give shape to a tubular blank by the application of pressure internally of the tube, said apparatus comprising an expanding former having relatively movable sections.

Another object of the invention is to provide a former in which provision is made for the guidance of a knife, whereby the blank after it has been shaped upon the former may be properly trimmed to size and slit prior to its removal from the former.

Still another object of the invention is to provide an improved form of knife particularly well adapted for use in connection with the guiding means embodied in the forming device.

Other objects and aims of the invention, more or less broad than those stated above, will be in part obvious and in part specifically referred to in the course of the following description of the elements, combinations, arrangements of parts, and applications of principles constituting the invention; and the scope of protection contemplated will appear from the claims.

In the accompanying drawings in which I have shown an illustrative embodiment of the invention; Figure 1 is an elevation of an apparatus embodying my invention, showing a tubular blank in place thereon ready for the shaping operation; Fig. 2 is a view similar to Fig. 1 but showing the apparatus expanded, and showing the form of the blank after such expansion; Fig. 3 is a perspective illustrating the subject matter of Fig. 2; Fig. 4 is a detail sectional view, partly in elevation, showing the knife and the guiding means therefor; and Fig. 5 is a perspective of a finished legging as an ex-

ample of an article in connection with the manufacture of which my invention may be employed.

Referring to the numerals on the drawings 1 indicates one of the sections of the expanding former and 2 the other section. These sections may of course have various configurations in accordance with the shape of the article which is to be manufactured. In the drawings, I have shown the sections of the forming member of such shape as that the apparatus may be used in connection with such a blank as is shown in Figs. 1, 2 and 3 in order to aid in the production of such an article as is shown in Fig. 5. In this illustrative embodiment, accordingly, the section 1 of the shaping device has an outwardly longitudinally straight surface 3, and is of substantially the same semi-circular cross section throughout its length; whereas the section 2 of the forming device has an outwardly longitudinally bulged surface 4, and while generally semi-circular in cross section, its cross sectional area is of course variable in accordance with said bulge. The opposed faces of said sections 1 and 2 are generally flat and straight, and the sections are preferably of the same length. Said sections 1 and 2 are connected together so that they may be moved toward or from each other in a direction transversely of their length. To that end, I may provide shafts 5 and 6 at the respective ends of the sections 1 and 2, said shafts being fixed against longitudinal movement in one of said sections, as for instance in section 2, and the other ends of said shafts 5 and 6 having threaded engagement with the other of said members, as for instance with the member 1, at the ends thereof respectively. In the present instance it will be noted that the shafts 5 and 6 are located at opposite ends of the forming members 1 and 2 so as not to interfere with the tubular blank which is interposed between said shafts. Thus the expanding pressure will be applied equally at opposite ends of the expanding members.

It will be evident that, the section 2 being secured to a base as shown, the sections 1 and 2 may be given relative movement toward or from each other, if the similar shafts 5 and 6 be moved in synchronism. Such movement may be accomplished as by means of a connecting shaft 7, which may be held in proper bearings upon the inner face

of one of the sections, as for instance section 2, said shaft 7 carrying at its upper and lower ends respectively miter gears 8, which engage respectively with corresponding gears 9 upon the shafts 5 and 6. As shown in Fig. 2, the shaft 6 which is preferably lowermost, may be the driving shaft, and rotation thereof effected by means of a crank handle or pulley 10 mounted upon the shaft, 10 and by means of some such parallel motion device as has been described the sections 1 and 2 may be caused to move toward or from each other equally throughout their length, so that when the blank has been 15 placed in position about the contracted forming device, said blank may be given the shape shown in Fig. 2 upon separation of the members 1 and 2 in the manner described. It will be noted that by locating 20 the driving shaft at the lower end of the device the forming members are free at their upper ends. This permits of the ready positioning of the blank thereon.

The sections 1 and 2 may be made of any 25 suitable material, as for instance iron, and I preferably make provision in the outer surface of said sections for the guidance of a knife or cutter which I may employ for trimming the expanded blank and for slitting it preparatory to its removal from the forming device. In the embodiment shown, 30 I provide grooves running around the sections 1 and 2 at proper distances apart near the top and bottom of the shaping device, in accordance with the desired length of the 35 finished article. The grooves at one end of the sections 1 and 2, which grooves of course register, are indicated by the numeral 12, and the grooves at the other end of the sections 1 and 2 are indicated by the numeral 13. I also provide a groove 14 running 40 longitudinally of the outer face of the section 1. I prefer that the groove 14 shall cut across and extend beyond the grooves 12 and 13 at the ends of the section 1, for reasons which will be apparent later. The 45 grooves as described would suffice to guide a knife so that the upper and lower edges of the expanded blank shown in Fig. 2 could be trimmed off by simply passing the knife around the sections 1 and 2, within the 50 grooves 12 and 13 respectively, and the blank might be longitudinally slit by passing it lengthwise of the section 1 when its point engages in the groove 14. I prefer however, 55 both for the sake of added strength in the device as a whole, and because of another resulting advantage, to cover the outer portions of each of the sections 1 and 2 which engage the blank to be stretched, with a 60 sheath or envelop of some rigid material, preferably steel, indicated in the drawings by the numerals 15. These metal sheaths are provided with kerfs 16 running parallel 65 to the several grooves 12, 13 and 14, said

kerfs being of less width than the grooves which lie beneath them, and extending in lines substantially medially of the width of the grooves. The result of this arrangement, as is clear from Fig. 4, is that I provide in effect under-cut grooves. In order to utilize this fact, I contemplate using in connection with the grooves a knife or cutter member 17, whose blade is adapted to pass through the kerfs in the metal sheath, 70 and which is provided with a heel 18 at the end of the blade and extending transversely of the blade, said heel being of a thickness so that it may pass into the kerfs in the sheath, but being of such a length that when 75 it is turned within the groove it cannot be withdrawn until its length is brought parallel to the length of the kerf. Thus the knife is effectively held in its proper relation to the groove. As before suggested the groove 80 14 at the front of the shaping device crosses the grooves 11 and 12 and extends beyond them respectively toward the ends of the member 1. This is in order that the knife 85 may be transferred directly from either one 90 of the grooves 12 and 13 to the groove 14, without taking out the knife.

As many changes could be made in the above construction and many apparently widely different embodiments of this invention could be made without departing from the scope thereof, it is intended that all matter contained in the above description or shown in the accompanying drawings shall be interpreted as illustrative and not in a 95 limiting sense. It is also to be understood that the language used in the following claims is intended to cover all of the generic and specific features of the invention herein described and all statements of the scope of 100 the invention, which as a matter of language, might be said to fall therebetween.

Having thus described my invention, what I claim as new and desire to secure by Letters Patent, is:

1. In an apparatus for use in manufacturing leggings; a plurality of formers adapted to receive a tubular blank about them and to be expanded relatively to each other for giving shape to said blank by expanding 115 means carried at opposite ends of one of said formers, each comprising a rotatably mounted screw having threaded engagement with another of said formers; a beveled gear fixed to each of said screws; and a shaft ro- 120 tatably mounted upon one of said formers having gears fixed thereto meshing with the gears on said screws; and one of said screws having an operating handle connected thereto for operating said entire expanding 125 means; said blank having a fullness at one locality and said formers being adapted, in effect, to transfer said fullness to a different locality through the operation of said expanding means.

130

2. The combination with the relatively movable sections of an expanding former adapted to receive an article about them and to be expanded within said article, of means for trimming off portions of said article, while said article is on said former, comprising an undercut groove having parts formed in at least two of the relatively movable sections of said former, means for maintaining the parts of said groove in alignment

as the sections of said former separate, and a trimming off tool in said groove, guided thereby, and being retained by the undercut walls thereof against displacement.

In testimony whereof I affix my signature 15 in the presence of two witnesses.

MORRIS ROSENWASSER.
